(57) **CLAIM**

The ornamental design for a combined wrist computer and phone, as shown and described.

DESCRIPTION

FIG. 1 is a top and side perspective view of a combined wrist computer and phone showing a new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a top and side perspective view thereof.

The broken line showing of a hand and forearm in FIG. 7 depicts environment. The remainder of the broken lines depict portions of the combined wrist computer and phone that form no part of the claimed design.

1 Claim, 4 Drawing Sheets
